UNITED STATES PATENT OFFICE

WILLIAM H. ROBBINS AND RAYMOND F. BOEHLER, JR., OF SPRINGFIELD, OHIO,
ASSIGNORS TO THE WILLIAMS COMPANY, OF LONDON, OHIO, A CORPORATION OF
OHIO

STEEL WOOL MACHINE

Application filed March 29, 1928. Serial No. 265,774.

Our invention relates to steel wool machines.

It is the object of our invention to provide a steel wool machine which operates continuously upon a single wire that is looped around supporting means, only one of which is driven, such wire being looped twice around the driving drum for every loop that passes around the idler drum.

10 It is a further object to provide such a machine of the vertical type in order that wool may be cut from both sides of the machine simultaneously.

15 It is a further object to provide in such a machine loops of wire in groups, such groups being spanned by a common cutting tool.

It is a further object of our invention to provide a novel form of tensioning means on the wire and of maintaining it on the driving 20 drum.

25 It is a further object of our invention to provide adjusting means for rigidly and permanently holding the cutting tool in cutting position when adjusted, but which may be modified in its adjustment to a very fine degree to get the exact setting of the adjustment either when the wire is stationary or when it is moving, thus eliminating the necessity for shutting down the machine to 30 adjust the tools.

Referring to the drawings:

Figure 1 is a side elevation of the machine;

35 Figure 2 is a top plan view of the left hand end thereof;

Figure 3 is a section on the line 3—3 of Figure 2;

40 Figure 4 is a top plan view of the entire machine partially broken away in the center indicating the double looping of the wire on the driven drum;

Figure 5 is an enlarged section through the driving and change speed gear mechanism;

45 Figure 6 is a side elevation of the tool adjusting mechanism with the wire guide and wire tensioning means in section together with a part of the bed in section;

Figure 7 is an enlarged top plan view of the tool holder;

50 Figure 8 is an enlarged side elevation of the tool holder;

Figure 9 is a section on the line 9—9 of Figure 6;

Figure 10 is a section on the line 10—10 of Figure 4;

Figure 11 is a section on the line 11—11 of Figure 4;

Figure 12 is a detail elevation of a portion of the grooving on the driving drum;

Figure 13 is a similar view of the driven 60 drum;

Figure 14 is a diagrammatic view in plan showing the arrangement of the looping of the wire on the driving and driven drums.

Referring to the drawings 1 is a bed for the machine in which is located the driving 65 mechanism. This mechanism consists of a driving motor 2 actuating through gears 3 and 4 the intermediate shaft 5 carrying a plurality of different sized gears 6, 7, 8 and 9 which are in turn engaged by the gears 10, 11, 12 and 13 respectively, which are loosely mounted upon the shaft 14 carrying the key 15 which engages with the slots 16 of the respective gears to key the gear so selected to turn with the shaft 14 so that the shaft 14 70 may be driven through the gear thus selected which are in mesh.

This key 15 is shifted by the shifting lever 17 carried on the shifting rod 18. The gears 19 and 20, respectively mounted upon the 80 shafts 14 and 21, serve to operate through the shaft 21 the take-up drum 22, the function of which will be hereinafter described. This drum 22 is actuated through the belt 23.

The shaft 14 drives through the worm 24 85 the worm gear 25 which is carried on the base of the drum shaft 26 of the drum 27. This drum is provided with a series of spaced grooves 28.

The bottom of the shaft is journaled at 29 90 in the base 1 while the top of the shaft is journaled at 30 in the top frame 31 which is supported at either end by the end frame members 32. Mounted on either side of the machine are vertically disposed side frame members 33 connected at their top and bottom to the respective top and bottom members 1 and 31.

These side frame members consist of vertically disposed plates having a plurality of 100

spaced projections 34 which carry in slots 35 the floating wire guides 36, the slots being arcuate and the bottoms of the wire guides 36 being also semi-circular. There is interposed between the surface of the slot 35 and the bottom of the guide 36 anti-friction rollers 37 which are journaled in the sides of the slot 35. The face of this guide 36 is grooved as at 38 to receive a group of wires preferably 10 6 in number.

The back of this wire guide 36 is provided with a pin 39 which extends through the projection 34 on the side wall 33, its rear end being connected to a spring 40 carried on a 15 rod 41. The rod 39 projects through an enlarged slot 42 formed in the projection 34 and the side wall 33 to permit of the rocking movement of the wire guide 36.

Adjacent the take off point on the side wall 20 33 to the driven drum we provide a wire tensioning means to maintain the wire in taut condition and in position. This consists of a cage 43 having a pair of spaced rollers 44 on which the wire 45 rides. Interposed between these rollers 44 and arranged on the opposite side of the wire is a pressure roller 25 of larger size designated 46 having a shaft 47 whose ends rest in spaced slots 48 within the cage 43, the outer end of the cage 49 carrying the screws 50, the ends of which engage the shaft ends 47 pressing the outer roller 46 against the portion of the wire which bridges the rollers 44 thereby placing the 30 wire under tension and maintaining it on the drum.

Turning to the cutting tool setting mechanism, it will be observed that the cutting tool is a broad tool 51 which spans a group of loops of the wire. This tool is adjustably 40 mounted by the set screw 52 in a cutting tool arm 53. This arm is vertically adjusted by the set screw 54 in a cutting tool holder 54a.

This holder is rotatably mounted on the shaft 55 in the bracket bearing 56 carried on 45 the side frame 33. On this shaft 55 is a worm gear 57 which is engaged by a worm 58 to give a micrometer adjustment to the holder of the tool it carries with respect to the wire 45. This worm 58 is mounted upon a shaft 50 59 having a shoulder 60 engaging with the worm block to take the thrust at one end while the rear end of the worm shaft 59 is supported in a sleeve 61 threaded into the worm block at 62 at the actuating end of the shaft. 55 The shaft is actuated by the hand wheel or knurled head 63.

This worm block is detachably mounted upon the holder by the bolts 64 and 65.

Thus, we provide a cutting tool that can 60 be adjusted longitudinally of the wire, vertically of the wire and at an angle to the wire.

Method of operation

65 The wire 45 is supplied from a drum or

reel 66 carried in a supporting holder 67. This wire passes over the idler drum 68 which is similar to the power driven drum 27 and thence passes beneath the cutting tools 51 to the driven drum 27 and thence passes around 70 the drum twice making a complete loop around the drum where it passes under the cutting tools on the other side of the machine. Cutting tools may be used either on one side or both sides, as the construction is the same. 75

The wire finally departs from the machine at the top of the machine whence it passes downwardly over an idler shaft 68a carried on a bracket 69 mounted upon the top frame 31. This wire descends to the drum 22 which 80 is a winding drum that is tapered outwardly from the point of delivery from the wire to the drum which causes the wire to move laterally, the free end of the wire being cut off 85 at intervals as desired.

This drum is actuated through the same series of power as the main machine but a clutch 70 is provided which permits a variable speed take-up so that while the wire is maintained at a constant tension by reason 90 of the take-up yet it will not be broken due to the increasing size of the drum of wire which is being wound.

By the application of the power to a single drum considerable economy in machinery and 95 loss of power is effected, the power is applied through the wire at one place with the minimum of slipping.

The tendency of the wire to vibrate is reduced materially by having it tensioned by 100 the double looping on the driving drum. The greater the tension the less chance for whipping and chattering of the tools.

It is further prevented by the very cheap but effective method of putting a tension on 105 the wire through the three steel rollers. This tension can be adjusted on the groups of loops while the machine is running.

The cutting tools having the several adjustments may be adjusted while the machine 110 is running by micrometer fineness which is heretofore not been possible.

In the operation of the machine, when the old wire is about used up and its rear end is about to pass in the machine the front end 115 of a new wire is welded to the old wire so that a continuous wire may pass through the machine and the machine will operate without a shut down.

It will be understood that we desire to 120 comprehend within our invention such modifications as may be necessary to adapt it to varying conditions and uses.

Having thus fully described our invention, what we claim as new and desire to secure 125 by Letters Patent, is:—

1. In a steel wool machine, a pair of spaced supporting sheaves, means to supply and take away wire from said sheaves, said wire being arranged to be looped completely about one 130

of said sheaves and about a portion of the other, and means to drive the sheave about which the wire is completely looped, and cutting means for said wire.

5 2. In a steel wool machine, a pair of spaced supporting sheaves, means to supply and take away wire from said sheaves, said wire being arranged to be looped completely about one of said sheaves and about a portion of the other, means to drive the sheave about which the wire is completely looped, cutting means for said wire, and means to place the tension on said wire.

15 3. In a steel wool machine, a pair of spaced supporting sheaves, means to supply and take away wire from said sheaves, said wire being arranged to be looped completely about one of said sheaves and about a portion of the other, means to drive the sheave about which the wire is completely looped, cutting means for said wire, means to place the tension on said wire, and means to guide said wire.

25 4. In a steel wool machine, a pair of spaced supporting sheaves, means to supply and take away wire from said sheaves, said wire being arranged to be looped completely about one of said sheaves and about a portion of the other, means to drive the sheave about which the wire is completely looped, cutting means for said wire, means to place the tension on said wire, and means to guide said wire in groups of loops in floating engagement with the cutting means.

35 5. In a steel wool machine, a bed, spaced vertical drums so arranged that wire may pass around the outside end of one of the drums and completely around the other of said drums, the wire being looped from drum to drum, means to supply wire to the machine, means to remove wire under tension from the machine, power means for driving the drum about which the wire is completely looped, cutting means for cutting the loops of wire, and means for driving the removing means.

45 6. In a steel wool machine, a bed, spaced vertical drums so arranged that wire may pass around the outside end of one of the drums and completely around the other of said drums, the wire being looped from drum to drum, means to supply wire to the machine, means to remove wire under tension from the machine, power means for driving the drum about which the wire is completely looped, cutting means for cutting the loops of wire, means for driving the removing means, and means to permit of the variation of speed of the removing means with respect to the speed of the machine.

55 7. In a steel wool machine, a bed, spaced vertical drums, one of which is driven, means for driving said drum, a side wall member, means for carrying a plurality of tools thereon, guiding means for wires thereon, tension-

ing means for wires thereon, said parts being so arranged that a single wire will pass around the outside end of one of said drums and completely around the other of said drums which is power driven before returning to the other drum, means to supply the wire and means to remove the wire under tension.

In testimony whereof, we affix our signatures.

WILLIAM H. ROBBINS.
